ROLLING MILL

Heinz Puppe, Neunkirchen, Germany

Application July 31, 1937, Serial No. 156,779
In Germany March 4, 1936

4 Claims. (Cl. 80—35)

This invention relates to a rolling mill with roll stands arranged in series for the continuous hot rolling of strip iron or broad band iron, more particularly strip or band iron having a breadth 5 greater than 600 millimetres.

Experience has shown that in these cases a profiling of the rolls such as is known in the manufacture of individual sheets or of individual piles or fagots, wherein the roll openings of the 10 successive roll stands are convex in shape, so that each roll opening is less convex than the roll opening of the preceding roll stand, is unsatisfactory, because the final products are not dimensioned correctly enough, the thickness of 15 the broad band iron produced fluctuates considerably, the condition of the edges leaves a good deal to be desired, and finally the continuous removal of scale between one roll stand and the next is hardly practicable.

20 In particular the obtaining or producing of a satisfactory surface in rolling strip iron of a breadth exceeding 600 millimetres presents very great difficulties, because the scale that forms on the surface of the strip can hardly be removed 25 in the short space between the successive roll stands, in view of the breadth of the band, so that it is rolled into the surface of the band, thereby leading to defective surfaces and even to a useless product.

30 Now according to the present invention these disadvantages are obviated by constructing the roll openings in the individual roll stands convex and concave, and by reversing this construction between successive roll stands, the magnitude of 35 the convexity or concavity, or in other words the angle that determines the magnitude of the convexity or concavity, preferably varying in such a way that the roll opening has its maximum thickness in the centre.

40 That the roll openings become progressively flatter will be self-evident.

The roll stands may be equipped, as multi-roll stands, with rolls of different diameters. This 45 succession of stands may then be followed in a known manner by multi-roll stands with straight rolls, the working rolls of which are of smaller diameter than the other rolls.

One embodiment of the invention is illustrated 50 by way of example in the accompanying drawings, in which.

Figure 1 shows the rolling mill diagrammatically in side elevation;

Figure 2 shows a section on the line 2—2 in 55 Figure 1;

Figure 3 is a front view of any one of the alternate roll stands I, III or V;

Figure 4 is a front view of any one of the roll stands II or IV;

Figure 5 shows in cross section the shape of the 5 roll opening in one group of stands, this roll opening being concave on the upper side and convex on the under side;

Figure 6 is a similar view of the roll opening 10 of the intervening stands which is convex on the upper side and concave on the under side;

Figure 7 is a view similar to Figure 5, but showing a narrower roll opening occurring at a later stage in the series of roll stands, and

Figure 8 is a similar view of the finishing roll 15

As will be gathered from Figure 1 the work-piece 6 enters the rolling plant from the left and travels through the individual roll stands I to V, 20 which are constructed as multiple roll stands, 25 each with two inner working rolls 1, 2 or 1', 2' of relatively small diameter, and two outer supporting rolls 3, 4 or 3', 4' of larger diameter. In other respects the construction of these roll stands, which are equipped with the usual driving 30 and adjusting means, is known.

As shown in Figures 3 and 4 the rolls 1 and 2' 35 are concave, and the rolls 1' and 2 are convex. The roll openings in the stands I, III and V are therefore convex as viewed from above and concave as viewed from below, whereas the roll openings of the stands II and IV are concave as viewed from above and convex as viewed from below.

Before, between and behind the roll stands are 40 provided rollers 5. As Figure 1 shows, the work may be given a looped form if this should be desirable.

Figures 5 to 8 show on a larger scale the shape 45 of the roll opening at 4 successive stages. In particular Figure 5 shows the workpiece 6a concave on the upper side and convex on the under side, as shaped by a convex upper roll and a concave lower roll, like those of the stands II and IV.

Figure 6 shows the workpiece 6b with a convex 50 upper surface and a concave under surface, as produced by a roll stand with a concave upper roll and a convex lower roll, as in the case of the roll stands I, III and V.

Figure 7 shows the workpiece 6c with a cross 55 section similar to that of Figure 5, except that it has been reduced in thickness in its progress through the rolling mill.

Finally Figure 8 shows the cross section of the 60 finished strip 6d.

The rolling operation proceeds as follows: When the metal enters the first roll stand, which may be equipped for example with a concave upper roll and a convex lower roll, the work receives a cross section which is convex on the upper side and concave on the lower side. Since in the next roll stand there is a convex upper roll and a concave lower roll, the work receives a cross section with a concave upper side and a convex under side. In succeeding roll stands there is again a concave upper roll and a convex lower roll, so that the work receives a cross section with a convex upper side and a concave under side.

This cycle of operations described above is repeated.

What I claim is:—

1. A rolling mill with roll stands arranged in series for the continuous hot rolling of strips and broad long bands of iron of a breadth greater than 600 millimetres, comprising roll stands arranged one behind each other, bottom working rolls and top working rolls mounted in said roll stands, the arrangement being such that the bottom working rolls of successive passes are alternately concave and convex, whereas the said top working rolls are alternately convex and concave.

2. A rolling mill with roll stands arranged in series for the continuous hot rolling of strips and broad long bands of iron of a breadth greater than 600 millimetres, comprising roll stands arranged one behind each other, bottom working rolls and top working rolls mounted in said roll stands, the arrangement being such that the bottom working rolls of successive passes are alter-

nately concave and convex, whereas the said top working rolls are alternately convex and concave, and the curvature of the concave side of a roll opening differing from the curvature of the convex side of the same roll opening.

3. A rolling mill with roll stands arranged in series for the continuous hot rolling of strips and broad long bands of iron of a breadth greater than 600 millimetres, comprising roll stands arranged one behind each other, bottom working rolls and top working rolls mounted in said roll stands, the arrangement being such that the bottom working rolls of successive passes are alternately concave and convex, whereas the said top working rolls are alternately convex and concave, and each roll stand including supporting rolls in addition to working rolls.

4. A rolling mill with roll stands arranged in series for the continuous hot rolling of strips and broad long bands of iron of a breadth greater than 600 millimetres, comprising roll stands arranged one behind each other, bottom working rolls and top working rolls mounted in said roll stands, the arrangement being such that the bottom working rolls of successive passes are alternately concave and convex, whereas the said top working rolls are alternately convex and concave, the roll opening between the working rolls of at least one roll stand at the end of the series being straight, and the finishing working rolls being of smaller diameter than the preceding rolls and each roll stand including at least two supporting rolls in addition to the working rolls.

HEINZ PUPPE.
